UNITED STATES PATENT OFFICE

EMIL C. HOPPE, OF ELIZABETH, NEW JERSEY

DESIGN FOR AN AMUSEMENT-PARK BUILDING OR ANALOGOUS STRUCTURE

Application filed May 31, 1930. Serial No. 35,871. Term of patent 14 years.

To all whom it may concern:

Be it known that EMIL C. HOPPE, citizen of the United States, residing at Elizabeth, in the county of Union and State of New Jersey, has invented a certain new, original, and ornamental Design for Amusement-Park Building or Analogous Structure, of which the following is a specification, reference being had to the accompanying drawing, forming part thereof.

The figure is a perspective view of an

amusement park building or analogous structure, showing my new design.

I claim:

The ornamental design for an amusement park building or analogous structure, as shown.

Signed at New York, in the county of New York and State of New York, this 28th day of May, 1930.

EMIL C. HOPPE.
